APPARATUS FOR IRRADIATING FOOD-STUFFS AND THE LIKE

Orrick H. Biggs, Beverly, Mass., assignor to Hy-grade Sylvania Corporation, Salem, Mass., a corporation of Massachusetts

Application December 2, 1938, Serial No. 243,574

6 Claims. (Cl. 62—89)

This invention relates to methods and apparatus for treating materials by radiation and with particularity to an improved form of sterilizing chamber.

5 An object of the invention is to provide a sterilizing chamber particularly suited to the housing of foods, food products, etc.

Another object is to provide an improved refrigerator having automatically controlled sterilization.

10 A further object is to provide an improved method of subjecting foods, food products, etc., to measured radiation by employing sterilizing radiations of predetermined and repeated duration.

15 A feature of the invention relates to a housing for foods, food products, etc., having on its interior a source of sterilizing radiations together with means for enhancing the sterilizing action 20 of said radiations.

25 Another feature relates to a refrigerator having an interior source of radiations which is rendered automatically effective for a predetermined duration each time a door or similar member is opened or closed.

30 A further feature relates to a refrigerator or similar device having its interior surface, or at least a suitable portion thereof, provided with a specially designed coating for efficiently diffusing and/or reflecting sterilizing radiations such as 35 ultra-violet rays or the like.

35 A further feature relates to the organization, arrangement and relative location of parts which go to make up a relatively simple and economical sterilizing refrigerator or similar device.

Other features and advantages not specifically enumerated will be apparent after a consideration of the following descriptions and the appended claims.

40 While the invention will be disclosed herein as embodied in particular forms of apparatus, it will be understood this is done merely for the purpose of explaining the invention. While, therefore, the drawing shows schematically a refrigerator embodying the invention, it will be apparent that the broad inventive concept can be embodied in other types of devices without departing from the spirit and scope of the invention.

45 Accordingly, in the drawing Figure 1 is a perspective view of a refrigerator embodying features of the invention;

Figure 2 is a sectional view of the refrigerator of Figure 1 with the door closed;

50 Figure 3 is a diagrammatic curve showing the

relation between intensity and duration of the sterilizing rays;

Figure 4 is a schematic diagram of one form of timing arrangement;

Figure 5 is a schematic circuit diagram of an alternative timing arrangement for controlling the radiation lamps according to the invention; and

Fig. 6 is a view of one form of lamp according to the invention.

10 Referring more particularly to Figures 1 and 2, the numeral 1 indicates any suitable enclosure or housing adapted to contain foods, food-stuffs, or similar materials which tend to change their taste or chemical characteristics by reasons of 15 bacteria or similar organisms. For convenience of description it will be assumed that the device 1 is a refrigerator of any well known construction.

While the drawing shows a refrigerator of the 20 artificial cooling type wherein the cooling unit 2 is refrigerated by gas, electricity, etc., it will be understood that any other manner of cooling the interior of device 1 may be employed, for example, by ice, evaporation, or the like. Furthermore, while the drawing shows the refrigerator 25 provided with a single main door or access member 3, it will be understood that any other form of access member, such as a window or the like, may be provided in addition to the main door 3.

Suitably mounted within the food compartment 30 or compartments of the refrigerator are a pair of lamps 4, 5, although it will be understood that in this respect the invention is not limited to any particular number or disposition of lamps. For example, instead of employing two lamps 35

disposed on opposite side walls of the refrigerator, one large lamp may be employed and suitably mounted within the compartment so as to radiate uniformly the entire interior of said compartment.

It will also be understood that if the refrigerator is provided with separate food compartments, then one or more lamps may be provided in each compartment. While, therefore, the drawing shows a refrigerator of the single compartment type provided with shelves 6 and 45

7, this is merely for securing simplicity in the drawing. Where a single lamp or pair of lamps is employed as shown in Figures 1 and 3, it is preferable that the shelves be of open-work construction so as to allow the sterilizing radiations 50

from the lamps to pass therethrough and thus enabling the lower and upper portions of the compartment to be radiated. If desired, these shelves may be of glass, quartz or other material which is transparent to the sterilizing radiations. 55

On the other hand, if non-transparent shelves are employed, then an additional lamp or lamps may be mounted between the shelves to insure sufficient radiation for the entire contents of the compartment.

While the invention is not limited to any particular character of sterilizing radiations, it is preferred to employ radiations in the form of ultra-violet rays between 2500 and 2800 Å. (Angstrom units) wave length. More particularly, the lamps 4, 5 may be designed to generate rays having maximum intensity between 2530 and 2540 Å. and with substantially negligible radiation above 2800 Å.

If desired, the lamps 4 and 5 may be of the indirect illumination type, that is, with their bowl portions provided with a coating which is capable of efficiently reflecting the ultra-violet rays. Thus the inner surface of the bowl portion of each lamp may be provided with a reflecting coating of aluminum in the manner disclosed in my U. S. Patent No. 2,123,706, issued July 12, 1938.

I have found that the paints or enamels ordinarily employed on the interior of refrigerators are not suitable for conserving or efficiently reflecting ultra-violet rays, and this is probably caused by the fact that ordinary paints or enamels as used in refrigerators absorb a very considerable per cent. of the ultraviolet rays which are useful for bactericidal purposes. I have found that if the interior of the refrigerator compartment or compartments is provided with a coating which is capable of reflecting to a considerable extent these bactericidal ultra-violet rays, the sterilizing action is improved and it is possible to employ lamps of smaller wattage. Entirely apart from the improved sterilizing action, therefore, the use of lower wattage lamps for the desired sterilizing action, enables less power to be used in maintaining the temperature of the compartment at a desired value. Thus, as indicated in the drawing, the major portion of the interior of the refrigerator compartment as well as the inner face of the door 3, is provided with a coating of aluminum or other similar material capable of efficiently reflecting the bactericidal rays. This coating may be applied in any well known manner as by spraying, by the Schoop process, or even by painting and baking. Preferably also, the coating is of diffusely reflecting character so as to reflect the rays as uniformly as possible throughout the entire interior of the compartment.

As pointed out above, one of the most serious drawbacks to the utilization of devices such as ultra-violet lamps on the interior of a refrigerator is that such lamps generate a considerable amount of heat, thus reducing the running efficiency of the refrigerator. It is highly desirable, therefore, to employ ultra-violet lamps with as low a wattage as possible consistent with the desired bactericidal action. However, the problem is further complicated by the fact that there is a certain minimum intensity and a certain minimum time below which there is very little effective sterilization. I have found that sterilization by ultra-violet rays of the character set forth herein is normally governed by photo-chemical laws; that is, the total amount of sterilization is directly proportional to intensity and also to duration, so that for a given degree of sterilization, one-half as much sterilizing intensity is required if the duration is doubled, and vice-versa. However, 75 while this relation is true for a relatively wide

range of intensities, at the low intensities there is a threshold value below which the relation does not hold, as indicated by Figure 3, wherein the point P represents this threshold intensity. If, therefore, the lamps 4 and 5 are designed to generate only a low intensity in the neighborhood of this threshold value, there will be considerable chance of the sterilization being ineffective or at least non-uniform. Instead, therefore, of employing low wattage lamps operating for a proportionately long time, I have found that reliable and uniform sterilization can be achieved without undue heat generation by employing relatively high intensity lamps which are allowed to operate intermittently for predetermined fixed intervals, preferably every time the door or other access member is opened and closed. Since low intensity lamps require a relatively long time to achieve satisfactory sterilization, it is entirely possible that foods may be inserted and withdrawn from the compartment before the necessary sterilizing action has taken place. This and other disadvantages are overcome by employing sources which produce intensities of bactericidal rays well above the threshold intensity, and which are allowed to operate for a proportionately shorter duration each time the door or other access chamber is closed after the insertion of food material or the like into the compartment.

By employing a narrow-band ultra-violet lamp, the greater part of the electrical energy impressed upon the lamp is transformed into useful bactericidal flux, whereas with ordinary ultra-violet lamps of the "broad-band" type, a great deal of energy is expended in producing ultra-violet and other rays which are useless for bactericidal purposes and are even detrimental to the taste of the food. By employing relatively high intensity ultra-violet lamps which are designed to produce a relatively narrow band of light wavelengths, e. g., 2500 to 2800 Å., and by operating these lamps for predetermined fixed and limited durations each time the door or other access member is closed after the insertion of food material, and by conserving the bactericidal flux through the intermediary of the aluminum coating, it is possible to achieve substantially complete and uniform sterilization of the materials within the food compartment, and with a minimum of undesired heat energy.

While any well known means may be used for timing and limiting the duration of the radiation each time the refrigerator door is closed, there are shown two alternative arrangements in Figures 4 and 5 of the drawing. Referring to Figures 1 and 2, it will be seen that there is mounted within the refrigerator a timing control device indicated generally by the numeral 8. Slidably mounted in a wall of the device 8 is an arm 9 which carries at its inner end a one-way rack 10 which is normally held in its forward position by spring 11. The device is so positioned within the refrigerator that just as the door 3 closes it engages the arm 9 and moves it against the action of spring 11. Rack 10 in sliding, engages the associated ratchet wheel which winds up spring 12. Spring 12 in turn rotates the commutator 13 which is controlled by a timing escapement (not shown). When the refrigerator door is open the disc 13 is in the position shown in Figure 4 70 wherein the brush 14 is out of contact with the metal segment 15. When, however, the spring 12 is wound up due to rod 9 being engaged by the door as above described, the disc 13 is rotated completing the circuit from mains 16 and 17 to 75

the lamps 4 and 5. Under control of the escapement (not shown), the disc 13 rotates in the reverse direction and after a predetermined time interval, the brush disengages segment 15 and thus breaks the lamp circuit. If desired, the escapement may be adjustably variable so as to vary the period of illumination of the lamps as desired. There is thus provided an arrangement whereby when the refrigerator door is open and then closed, the timing mechanism is set into operation to maintain the ultra-violet lamps lighted for a predetermined fixed interval. It will be understood of course that instead of providing a single semi-circular segment 15, this segment may be replaced by a series of separate segments so as to repeat the illumination of the lamps at predetermined spaced intervals while the disc 13 is rotating.

Instead of employing an escapement which is wound up by a rack and pinion, an ordinary electric clock may be employed, the circuit of which is completed only when the refrigerator door is closed. The clock may then drive a multi-segment commutator to continue the intermittent illumination of the lamps.

Referring to Figure 5, there is shown an alternative arrangement wherein the door is provided with two insulated metallic segments 18 and 19 which, when the door is closed, bridge associated contact sets 20 and 21, 22 and 23, insulatingly mounted on the framework of the refrigerator. When the door is open the circuits to the relays 24 and 25 are broken. When relay 25 is normal, the lamps 4 and 5 are disconnected from the mains 26 and 27. As soon as the door 3 closes, a circuit is completed from main 26, through the lower contacts of relay 24, winding of relay 25, contacts 21, 18, 20, to the main 27. Relay 25 immediately operates and causes lamps 4 and 5 to light. Relay 25 is preferably of the "fast-to-operate slow-to-release" type and may take the form of a dashpot relay, a thermostat relay, or the like. As soon as relay 25 operates, it completes through its lower contacts an operating circuit for relay 24, which upon operating, becomes locked under control of contacts 23, 19 and 22. When relay 24 operates it breaks the circuit for relay 25 which begins to release. After a definite time interval relay 25 completely restores to normal and breaks the circuit to the lamps which stay dark thereafter until the door is again opened and closed to repeat the foregoing cycle of operations.

While specific apparatus and circuits are disclosed herein, it will be understood that the invention is not limited thereto and that various changes and modifications may be made therein without departing from the spirit and scope of the invention. For example, while the drawing shows lamps 4 and 5 of the spherical bulb type, any other shape of lamp may be employed, for example as illustrated schematically in Figure 6, which represents in "half scale" size a lamp that has been found to produce the desired results. This lamp comprises in general a tubular body 28 which is evacuated and provided with a filling of an inert gas such as neon at approximately 8 millimeters pressure, or with helium at approximately 12 millimeters pressure, or a suitable mixture of these gases. The tube 28 is preferably made of material capable of transmitting rays in the band between 2500 Angstrom units and 2650 Angstrom units. For example, this tube may be made of "Corex" tubing and preferably the center section 29 has a very thin wall section,

preferably less than one-half mm. in thickness. The electrodes 30 and 31 are preferably in the form of molybdenum coils which are sealed into and supported at the ends of the tubes in any well known manner. The particular lamp shown is designed to operate at an impressed voltage of 220 V. A. C. and with a current of 12.5 milliamperes flowing therethrough.

In a lamp of the type described, the electrode drop is generally large and fixed, and for that reason it might be thought that making the lamp long, so that the drop in the gas would be as large a proportion as possible of the total drop across the lamp, would be best. However, I have found that where the lamp is operated in a refrigerator the lamp is best made short, so that its length between electrodes is not greater than 3 inches, and is preferably about two inches. This is apparently due to the ultra-violet output of the lamp being greater at temperatures somewhat above the usual refrigerating temperatures. The lamp temperature is best below 120° F., however.

The shorter lamp operates at a higher temperature. For the same reason the current through the lamp should be at least 40 milliamperes per square centimeter of discharge tube cross section. The current through the lamp will, of course, depend on the voltage of the circuit from which the lamp is operated, and on the ballast resistance or reactance in series with the lamp. The preferable lamp temperature is about 90° F.

A lamp of the type described emits chiefly radiation of about 2536 to 2537 Angstrom units, which is extremely effective for treating foods for sterilization, vitaminization or other purposes without harming the taste of the food. Butter, lard, meats, milk, and other fatty foods, which will change taste markedly before sterilization is obtained when sunlight or a high pressure mercury arc is used for the purpose, will not change taste appreciably under the influence of the lamp described, even when the exposure is 100 times that needed for sterilization. Meat in particular can be kept longer, and at temperatures above the usual refrigeration temperatures, without spoilage.

This application is in part a continuation of application Serial No. 732,431, filed June 26, 1934, which has been issued on January 24, 1939, as U. S. Patent No. 2,145,196.

The refrigerator temperature generally will be in the neighborhood of 40° Fahrenheit, but may be raised considerably above that, if desired, say to 50° Fahrenheit, due to the action of the ultra-violet radiation in aiding refrigeration.

Thermionic electrodes may be used if desired, but in that case it may be necessary, for some foods such as milk, to blacken the glass near the electrodes to prevent the radiation from the heated electrodes falling on the food to be treated. Some foods are easily spoiled by visible light.

In a refrigerator of the electrical or mechanical type, where the refrigeration is produced for example by compressing a gas in one part of a sealed container, and allowing the gas to expand in another part of the sealed container, which part is placed in the compartment to be refrigerated, the compressor is generally driven by an electric motor. The motor may be controlled by a switch operated by a thermostat set in the compartment to be refrigerated, being started when the temperature rises above a fixed value, and being stopped when the temperature drops below another fixed value. In some cases, the motor is controlled by a switch operated by the

pressure in the gas to be compressed. When the pressure drops, a valve operates the switch which starts the motor, and when the pressure rises sufficiently the valve opens the switch, stopping the 5 motor.

The more often the refrigerator door is opened, the more the air in the refrigerator is changed, and hence the more it necessitates sterilization. I may, therefore, connect the terminals supplying 10 the sterilizing lamp current directly across the compressor motor terminals, so that when the compressor is running, the lamp is in operation, and when the compressor is not running, the lamp is not operated. Since the more often the refrigerator air is changed, the more often the refrigerator operates, this arrangement is desirable.

If desired, a door switch may be connected in series with the line from the motor to the lamp, to insure that when the refrigerator door is open 20 the lamp is extinguished, thus protecting anyone who may look into the refrigerator, from the ultra-violet rays.

The sterilizing lamp may require a higher voltage than is ordinarily available from the line 25 with which it is used. When alternating current is available, a transformer can be used to get the desired voltage; when direct current must be used, however, the lamp may be connected across the motor armature or commutator, through a 30 transformer if desired.

The sterilizing lamp shown in Figure 6 has its electric terminals at opposite ends of the tube. If desired, the terminals may be brought out at the same end of the tube, the electrode at 35 the opposite end being supported from the terminal end by an insulated metal rod running axially along the center of the lamp tube.

What I claim is:

1. The combination of an ultraviolet lamp 40 comprising a sealed tubular envelope of Corex glass transmitting radiations at 2537 Angstrom units, an atmosphere of inert gas at low pressure and mercury vapor within said envelope, electrodes about 2 inches apart and within said 45 envelope at each end thereof, apparatus for operating said lamp at a current density of 40 milliamperes per square centimeter, a refrigerating chamber around said lamp, a door in said refrigerating chamber, means actuated by the 50 closing of the door for starting the operation of the lamp, and means actuated by said first mentioned means to extinguish the lamp after a predetermined interval.

2. The combination of an ultraviolet lamp 55 comprising a sealed tubular envelope of Corex glass transmitting radiations at 2537 Angstrom units, an atmosphere of inert gas at low pressure

and mercury vapor within said envelope, electrodes within said envelope at each end thereof, said electrodes being placed close together to insure heating of the mercury vapor to an efficient radiating temperature, a refrigerating chamber around said lamp, a door in said refrigerating chamber, means actuated by the closing of the door for starting the operation of the lamp, and means actuated by said first-mentioned means to extinguish the lamp after a predetermined interval. 5 10

3. The combination of a food storage compartment refrigerated to a temperature of about 40° Fahrenheit, apparatus for operating an ultraviolet lamp in said refrigerated compartment at 15 a current density of about 40 milliamperes per square centimeter, and an ultraviolet lamp so operated in said compartment, said lamp comprising a sealed tubular envelope of Corex glass transmitting radiations at 2537 Angstrom units 20 in wavelength, an atmosphere of an inert gas at low pressure and mercury vapor within said envelope, and electrodes within said envelope at each end thereof, said electrodes being arranged substantially to prevent the emission of visible 25 light from themselves and being spaced no more than 3 inches apart so that the lamp efficiency will be increased by operation above the ambient temperature in the refrigerator.

4. The combination of a compartment refrigerated to a temperature satisfactory for food storage, but inefficient for operation of a mercury vapor ultraviolet lamp, apparatus for operating a low-pressure close-electrode ultraviolet lamp at a current density sufficient to operate said lamp 30 at a temperature enough above the ambient refrigerator temperature to be efficient but not sufficient to increase the electrode temperature to the point where substantial visible light is emitted from the electrodes, an ultraviolet lamp 35 comprising electrodes at each end of a sealed Corex glass tube transmitting radiation of 2537 Angstrom units wavelength with electrodes within said tube and at each end thereof, said electrodes being placed close together to insure heating of the lamp to a temperature substantially 40 above the ambient refrigerating temperature with the current density employed. 45

5. The combination of claim 4, in which the apparatus for operating the lamp at the proper current density is an impedance in series with the lamp. 50

6. The combination of claim 4, in which the apparatus for operating the lamp is an impedance in series with the lamp, and in which the electrodes are placed no more than 3 inches apart. 55
